METHOD OF MANUFACTURING METAL CLIPS OR LINKS

Victor J. Del Giudice, Detroit, Mich., assignor to
 L. A. Young Spring & Wire Corporation, Detroit, Mich., a corporation of Michigan

Application February 14, 1942, Serial No. 430,848

6 Claims. (Cl. 59—35)

1

The present invention relates generally to the manufacture of metal clips or links such, for example, as clips or links which are used for interconnecting in series a plurality of shells or cartridges to provide a so-called cartridge belt or strip for use with a machine gun. As will be understood, the clips or links and the shells or cartridges together form the belt and the cartridges themselves function as hinge pins or the like to join the clips or links together in the formation of the articulated belt. The invention also contemplates, however, the production of a plurality of other articles of like or similar nature. Heretofore, in the manufacture of such belt clips or links, from a strip or ribbon-like length of metal, a considerable portion of the metal of the blank strip became scrap and thus waste material during the method or process of forming the clips or links. It is, therefore, one of the important objects and advantages of my invention to provide an improved method or process and the means or mechanism for carrying it out, in which a plurality or succession of clips or links are formed from a length of stock, such as a ribbon-like piece of steel, by a continuous or progressive process or method, and in which a minimum of waste material or scrap occurs.

A further object of the present invention is to provide an improved method or process for manufacturing metal clips or links for the foregoing or other purposes by virtue of which a plurality or series of clip-forming operations are performed simultaneously on the blank or ribbon-like piece of stock during the progressive movement or advance of the stock from station to station while carrying out the various steps of the method or process.

Another object of the present invention is to provide an improved method or process of the foregoing character by virtue of which the successive clips or links may be individually subjected to a preforming step or operation while remaining an integral part of the blank or work strip without changing or otherwise affecting the position or location of the blank during the preforming operation.

A further object of the present invention is to provide an improved method or process of the foregoing character in which the clips or links are subjected to a preforming operation which causes a slight movement of a portion of the clip undergoing said preforming operation relative to the adjacent clips and the remainder of the strip or work blank without, however, causing any movement whatsoever of said adjacent

2

clips or the remainder of the blank or work-piece.

Another object of the present invention is to provide an improved method or process of the foregoing character which includes a succession or series of steps for forming from a single, continuous blank or ribbon-like strip of metal, a plurality of finished clips or links, in which the method or process includes novel shearing operations which permit the later preforming operation on a portion of each of the clips in the blank while said clips remain a part of the blank or work strip.

A further object of the present invention is to provide an improved method or process for manufacturing metal clips or links by virtue of which the lead or forward portion of one clip or link and the following or rear portion of the next advanced link are so formed in the blank or strip of material as to interfit one within the other and thus eliminate, to a large extent, the production of scrap and thus waste metal between adjacent clips.

The above and other objects and advantages of the foregoing invention will appear from the following description and appended claims when considered in connection with the accompanying drawings forming a part of this specification wherein like reference characters designate corresponding parts in the several views.

In said drawings:

Fig. 1 is a plan view of a portion of a strip or blank of metal illustrating the results of the various steps or operations of the improved method or process embodying the present invention.

Fig. 2 is a plan view of a metal clip or link produced by the method of the present invention.

Fig. 3 is a plan view, partly in section, and partly broken away, illustrating a portion of my improved method or process and portions of the apparatus for carrying it out, for producing clips or links in accordance with the present method.

Fig. 4 is a continuation of Fig. 3; the right-hand end of Fig. 3 and the left-hand end of Fig. 4 should be joined to show a continuous method or process. Separation of the method or process and the mechanism or apparatus for carrying it out was done so as to reduce the length of the figure which could not have been placed in desirable scale on the drawings in a single figure only.

Fig. 5 is an enlarged longitudinal section taken substantially along the line 5—5 of Fig. 3, looking in the direction of the arrows.

Fig. 6 is an enlarged transverse sectional view taken substantially along the line 6—6 of Fig. 3, looking in the direction of the arrows.

Fig. 7 is a transverse sectional view, on an enlarged scale, taken substantially along the line 7—7 of Fig. 3, looking in the direction of the arrows.

Fig. 8 is an enlarged transverse sectional view taken substantially along the line 8—8 of Fig. 3, looking in the direction of the arrows.

Fig. 9 is a transverse sectional view, on an enlarged scale, taken substantially along the line 9—9 of Fig. 3, looking in the direction of the arrows.

Fig. 10 is an enlarged longitudinal sectional view taken substantially along the line 10—10 of Fig. 4, looking in the direction of the arrows.

Fig. 11 is a transverse sectional view, on an enlarged scale, taken substantially along the line 11—11 of Fig. 4, looking in the direction of the arrows.

Fig. 12 is an edge view of a completed clip or link which was made in accordance with the process of the present invention, with the exception of a final operation or series of operations for giving the clip its final form or shape as shown; and

Fig. 13 is a plan view of the completed clip or link of Fig. 12.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the scope of the appended claims.

Previous attempts have been made to produce cartridge clips or links by progressive methods or processes from a single strip or blank of metal but in all such cases considerable waste material or scrap has resulted from the carrying out of such methods or processes. So far as is known, no one has heretofore evolved a method or process by which it has been possible to produce a plurality or series of clips or link members for use in connection with shells or cartridges, from a single strip or blank of material, which method included a preforming step whereby a portion of each of the successive clips or links was preformed while remaining an integral part of the strip or blank, without in any way affecting the position, location or condition of the remainder of the strip or blank. Therefore, it is an important purpose of the novel method or process of forming clips or links in accordance with the present invention, to form progressively a plurality or series of clips or links having interfitting portions, in which the method or process includes the novel step of preforming a portion of a clip at a predetermined stage of the method, during which preforming operation a portion of said clip is caused to move longitudinally relative to the next adjacent clip with which it interfits and also relative to the entire blank or strip of material, which latter remains in its normal position and condition during the preforming operation.

Moreover, it is a further important feature of the present invention to provide an improved method or process which includes shearing operations or steps which are so arranged and carried

out as to make possible the preforming operation of a later step in the method or process and to permit the aforesaid movement of the clip or link member during the preforming operation relative to the remainder of the blank or strip of material from which the clips or links are being formed.

Referring now to the drawings, in Fig. 1 there is shown, somewhat schematically, a strip or length of metal stock from which is formed, by a succession or series of preferably die operations or steps, metal cartridge or shell clips, one such clip being shown at the right of Fig. 1 and in Fig. 2, after the final operation or step of the present method or process has been completed.

In Figs. 3 and 4 there is shown, somewhat more in detail, the blank or strip of material, indicated as a whole at 15, and the operations or steps performed upon said material at the various stages or stations of the method or process, together with portions of die forming mechanism or apparatus for performing the various steps or operations of said process or method.

In general, the present method or process, as disclosed herein, comprises a first step or operation performed at station A (Fig. 3) which involves a shearing operation by a shearing die (see Figs. 3 and 5) to form a portion of the outline of a single clip from the stock or strip 15, said clip being indicated as having a tongue portion or lead end 16 and a pair of slits or cuts 18 defining a portion of the outline of the body of the finished clip, see Fig. 1. During the shearing operation at station A, a simultaneous punching operation is performed to produce a substantially rectangular hole or opening 17 which is located in the blank in spaced relation to and in advance of the lead end or tongue portion 16 of the partially formed clip (see Figs 3 and 5).

The stock or strip 15 moves from station A to station B at which station a pilot 26 (Fig. 5) carried by an upper die member enters the hole or opening 17 just described so as to locate or position the blank 15 properly for the performance of the second step or operation of the method. The second step, as shown, constitutes a second shearing operation performed by a shearing punch carried by an upper portion of the die mechanism or apparatus, see particularly Fig. 5. This punch shears the metal between the hole 17 and also in the region of the tongue and outline 18 and thus provides a second or further cut as indicated by the cut-lines 19 in Figs. 1, 3 and 5. It is to be noted at the left end of the strip 15 in Fig. 1 that the width of the tongue or lead portion 16 of the clip is given as approximately .55 inch which indicates the width or location of the shear or parallel cuts which occur at station A. The second shearing operation performed at station B effects a second cut so that the blank is slit in the region of the lead end or tongue 16 at a width of approximately .59 inch, thus leaving a space or clearance of approximately .020 inch as shown at 22a between the tongue or lead end 16 of said clip and the partially formed leg portions 23 of the adjacent clip to the right.

From station B, the blank or strip of material 15 moves to station C at which station a trimming operation is performed to remove or punch out the metal at opposite sides of the body portion 16a of the partially formed clip, along the lines or cuts indicated at 18 and 19, to provide the pair of openings 21, as seen in Figs. 1 and 4. At station C a second operation is performed simultaneously with the trimming operation, this

latter operation being performed by a round punch which removes the metal web or piece 20 (see Figs. 1 and 3) to provide the space or opening 22 between the legs 23 of the next adjacent clip to the right.

The strip or workpiece 15 is further advanced from station C toward the right to station D at which point the preforming operation on the body portion 16a of the clip occurs. During this preforming operation which will be described in detail hereinafter, the tongue or lead end 16 of the clip will be drawn or moved to the left of Figs. 1 and 4 and relative to the legs 23 of the next adjacent clip to the right in these figures to provide flared portions 24 in the body portion 16b of the clip. This movement of the tongue or lead portion 16 and the body portion of the clip relative to the legs 23 of the next adjacent clip to the right, is permitted or made possible by virtue of the combination of the first and second shearing operations at stations A and B, respectively, since these shearing operations have provided or produced the clearance 22a as indicated at the right end of Fig. 1 and also in Fig. 4.

It will be understood that the clip or pair of adjacent clips which are described above as being formed, have remained an integral part of the blank or stock 15 throughout all of the operations performed at stations A, B, C and D.

From station D, the strip moves toward the right to station E. At station E a separating or severing operation or step takes place during which the first two adjacent clips at the right-hand end of the blank are separated and their adjacent corners rounded, as shown at 49 in Fig. 4. Thus the clip 51 to the right of the blank of Fig. 4 is now no longer a part of said blank and has been formed into the shape and configuration as indicated herein and in Fig. 2. This finished clip as completed by the present method comprises a lead portion or tongue 116, a body portion 16b with flares 24 located at opposite lateral sides of the body portion and a bifurcated portion comprising the legs 23a whose inner ends are cut away at their inner opposed longitudinal edges to provide the opening indicated at 11a.

It will be understood that while I have described above the series of operations performed at the different stations, namely stations A to E inclusive, upon a pair of adjacent clips, it will be understood that after the blank or work strip 15 has been fed through all of the operations at the several stations described above, the bringing or moving together of the male and female die members and associated parts will perform, simultaneously, the entire series or group of operations on the blank or strip of material. In other words, the shearing, piercing or punching, trimming and preforming operations, as described above, as well as the separating operation at station E, are all performed simultaneously and since the blank or work strip 15 is fed progressively through the apparatus from station to station, a substantially continuous series of operations are performed upon the workpiece so as to produce, with each advance movement of the workpiece, a completed clip or link member such as that shown as a whole at 51 in Figs. 2 and 4.

Referring now particularly to Figs. 5 to 11 inclusive of the drawings, suitable apparatus is shown for the purpose of carrying out the various operations or steps of the process which occur or take place at stations A, B, C, D and E, described above. It will be understood that any suitable die apparatus or mechanism may be em-

ployed for carrying out the present method or process, that being shown in the drawings being merely illustrative of a suitable type of apparatus, means or mechanism for this purpose. It will be understood further that if and when desirable, the die mechanism may be rearranged so that the strip or blank of material 15 may be fed longitudinally through the apparatus or mechanism on edge. In such a case, the apparatus would be arranged in a horizontal plane with the male and female portions or parts or the dies, etc., having relative movements toward and away from one another in a similar plane. Moreover, if desirable, the positions of the male and female parts of the apparatus as shown in the accompanying drawings, could be reversed.

Station A

Referring now particularly to the apparatus or mechanism located at station A and shown in Figs. 3, 5 and 6 of the drawings, 30 represents as a whole the upper die head or member which, as shown, carries a male die member or shearing punch 34 which is adapted to move downwardly and into position as shown in Fig. 5 in cooperation with the lower or female die member 31 of the apparatus. It will be understood that as the shearing punch or member 34 moves downward, it shears the metal of the blank 15 to provide the outline for the tongue portion 16 and the body portion 16a of the first clip as defined or shown by the cuts or lines indicated at 18 in Fig. 1. The portions 16, 16a will be moved downward to the full line position and in contact with the upper surface or face of a spring-pressed pad 35 which is normally urged upward by virtue of springs 36. After the upper die member 30 and the shearing punch 34 have moved upward out of contact with the female die member 31, the pad 35 returns the portions 16, 16a of the blank to their broken line position substantially flush with the blank or strip 15, as shown in Fig. 5. A stripper is provided for assisting in the work of the shearing die member 34, said stripper being indicated as a whole at 32 in Figs. 3, 5 and 6.

Operating simultaneously with the shearing member 34 and carried by the die head 30 at station A, is a punch member 25 carried by head 30 which punch serves to pierce the blank of metal 15 and to remove therefrom a piece of scrap metal 25a, see particularly Fig. 5. The punch 25 moves downward with respect to the female die member 31 and thus forces the pierced metal piece 25a into a suitable channel or opening formed in the lower die member. The punch 25 forms the hole or opening 17 as clearly seen in Fig. 1 of the drawings. It is to be noted that this hole 17 is located in advance (to the right) of the lead end or tongue 16 of the partially formed clip. This hole 17 provides a portion of the adjacent clip located to the right of the tongue 16. The shearing operation, performed by the member 34, shears the metal of the blank 15 to provide the tongue or lead portion 16 which, as shown, has a width of approximately .55 inch. The punching or piercing operation performed by the punch member 25 not only forms the beginning of the next adjacent clip or link member to the right of the tongue 16, but also determines or prelocates the position of the second clip member to be formed in the blank.

By reference to Fig. 6 of the drawings, it will be seen that the upper die member or head 30 is reciprocably guided above and with relation to the lower die member or base 31 by means of

a plurality of vertical columns or posts 33, only one such being shown.

Station B

From station A, reference being had particularly to Figs. 3, 5 and 6, the blank or stock 15 moves toward the right of Fig. 3 to the second stage or station of the process, designated station B. At station B (Figs. 3 and 7) the blank is subjected to a second shearing operation by means of a shearing die member 38 which subjects the previously sheared portion of the blank to a further shearing operation as indicated by the lines 19 in Figs. 1 and 5. During this shearing operation, the width of the shear adjacent the tongue portion 16 of the partially formed clip is increased to approximately .59 inch, thus producing a clearance or space between opposite side edges of the tongue 16 and the adjacent portions of the blank of a width of approximately .020 inch. It will be noted, see particularly Fig. 5, that the shearing die member 38 has associated with it a downwardly extending or projecting pilot 26. This pilot is adapted to enter the previously formed hole or opening 17 in the blank or workpiece 15 and thus position or properly locate the blank with respect to the second shearing die mechanism.

The upper die member or shearing device 38 moves downwardly and shears the blank to extend the shear along the lines 19 from the slot or opening 17 rearwardly past the tongue portion 16 and in parallelism to the shear or cuts 18 shown in Fig. 1, this second or increased shear being indicated by the lines designated 19. As the shearing member 38 moves downward, it shears the metal blank 15 and moves it into contact with a spring-pressed pad 39 located in the lower die 31, said pad being normally urged upward by springs 40. When the head 30 carrying the shearing member 38 and pilot 26 are retracted in an upward direction, the spring-pressed pad 39 returns or moves the sheared portions of the blank 15 to the broken line position as shown in the right portion of Fig. 5. Thus, the portions 20 and 16 of the blank 15 will be returned to substantially their original position in the blank so as to permit the entire blank to be moved further toward the right until it reaches the next station.

With respect to the shearing operation performed at station B, attention is particularly directed to Fig. 7 of the drawings wherein an enlarged transverse section through the second shearing means or apparatus is shown. It will be clearly seen from an examination of Fig. 7 that the first shear line is indicated at 18 and the second line of shear at 19. Thus the distance between the two lines of shear, namely the first shear 18 and the second shear 19, represents the amount of clearance or space which, as stated above, is approximately .020 inch.

Station C

Referring now particularly to station C as best seen in Figs. 3, 8 and 9, there is performed, at this station, a so-called trim operation which is combined with a punching operation to remove portions of the blank which have been previously subjected to the shearing operations just described.

Referring particularly to Fig. 8, there is shown an upper die member 30 and a lower or female die member 31, together with an interposed stripper, shown as a whole at 32. The trim operation at station C is performed preferably by a trim punch

42 which is provided for the purpose of removing metal on the opposite sides of the body portion 16a of the partially formed clip to provide slots or openings on opposite sides thereof, as seen at 21 in Figs. 1 and 4. As the shearing punch 42 moves down toward the base or female die member 31, metal slugs 21a are removed from the blank, see particularly Fig. 8. These slugs are pushed downwardly into suitably located openings or channels formed in the die member 31.

Referring now particularly to Figs. 3 and 9, it is to be understood that a punching operation occurs simultaneously with the trimming operation performed by the trim punch 42. The upper die member 30 carries a preferably round punch member 27 which, when said upper die member moves down toward the lower die member, carries the punch 27 into contact with the previously sheared portion 20 of the blank to remove said portion, see particularly Fig. 9, and to leave a space or opening 22 in the blank, see Figs. 1, 3 and 4, which is defined on opposite sides thereof by the bifurcated portion of the next adjacent clip to the right which includes, as shown, the leg portions 23. After the combined trimming and punching operation has been performed at station C, and the upper die member with attached trim punch 42 and slug-removing punch 27 have been retracted or moved upwardly out of contact with the blank 15, said blank is moved forwardly or to the right until it reaches station D.

Station D

Referring now particularly to the operation performed at station D and with particular reference to Figs. 4 and 10 of the drawings, it will be seen that the nearly completed clip or link member is still an integral part of the metal strip or workpiece 15. At station D, the apparatus or mechanism includes an upper die member 44 carried by the head 30. The underside of the die member 44 is provided with a pocket or recess for receiving and supporting a preforming die member 45. The lower or female die member 31 is provided with a pocket or recess which conforms to the shape of the preforming die member 45 and is provided with a bore in which a reciprocable spring-pressed plunger 46 is located, the spring not being shown. When the preforming die 45 moves down into contact with the clip or link member, the longitudinal edge portions of the body 16b of the clip are pressed downwardly and flared as shown at 24. When the upper die holder and preforming die move away from the lower die member and the preformed clip or link, the spring-pressed plunger 46 functions to lift the clip member out of the pocket or recess formed in the female or lower die member 31 so that the clip, which is still attached to the workpiece or strip 15, can be moved with the strip toward the right in Fig. 4 to the next operation which is performed at station E.

Station E

Referring now to the operation performed at station E and with particular reference to Figs. 4 and 11 of the drawings, it will be seen that the upper portion or head 30 of the die mechanism carries a so-called separator die 48. The separator die 48 is adapted to move downwardly into the space formed in the lower or female die member 31 and during this downward movement, the combined separator and cutting die member 48 removes the web-like strips 15c, 15c, which are disposed opposite the flared portions 24, 24 of the clip and

simultaneously trims and rounds the corners of the leg portions 23a of the clip 51 at the right-hand end of Fig. 4 and the corners of the next adjacent clip 52. These rounded corners or radii are shown at 49 in Fig. 4. By removing the connecting strips or portions 15c, 15c, the combined separator and cutting die member 48 thus severs or separates the two adjacent clips, whereupon the clip shown as a whole at 51 is entirely separated from the next adjacent clip 52 in the line, it being understood that the clip 52 remains an integral part of the workpiece or strip 15 until said clip has reached the position vacated by the clip 51 as shown in Fig. 4.

As seen in Fig. 4, the stripper 32 terminates somewhat in advance of the mechanism located at station D, since no stripper is needed for the operations performed at stations D and E. If, however, it proves desirable to continue the stripper to include the mechanism located at stations D and E, this can be easily done.

The successive clips, such as the clip 51, are removed after the operation performed at station E and are shaped or completed by any suitable means or apparatus (not shown) and in any suitable manner to provide the finished clips such as the clips 60 shown in Figs. 12 and 13.

From the foregoing it will be seen that I have provided a novel method or process and suitable means or mechanism for carrying it out in which a plurality of metal clips or links of the character described are formed from a single blank or strip of metal and in which all of the clips remain a part of the blank until the two adjoining clips at the lead end of said blank reach the last operation of the process or method which is performed by the mechanism located at station E. It is to be noted particularly that there is but a minimum of waste of material as the result of slugs or scrap removed from the blank during the method or process of forming the clips. Moreover, it will be seen that the tongue members or lead ends of the clips interfit with the bifurcated following portions or leg members of the next advanced clip in the strip or workpiece. In this manner, considerable material is saved since, it is to be noted particularly, the only material removed as scrap between adjacent clips is that which is punched out to form the slot or opening 17, 17a, the blank piece 20 between the opening 17 and the adjacent lead end or tongue of the next clip to the left, the material which is removed from opposite sides of the body portion 16a, 16b of the clip, to provide the openings 21 on opposite sides of the body portion, and finally the narrow webs, strips or connecting pieces 15c which join the adjacent clips at their outer longitudinal edge portions. Thus, the total scrap removed from the blank is relatively small. Furthermore, attention is again invited to the fact that by virtue of applicant's manner of using shearing dies or members, it is possible for the lead ends or tongues of the successive clips to be moved longitudinally relative to the body of the blank and the next adjacent clip without in any way affecting the positions of the blank itself or the other clips being formed therefrom.

I claim:

1. That improvement in the art of producing a plurality of metal articles of like character extending across the entire width of a single metal blank by a substantially continuous method, which method comprises the steps of shearing said blank to provide a portion of one of said articles and simultaneously piercing said blank at a point removed from and in advance of the

sheared portion thereof, advancing said blank and locating the same while simultaneously performing a second shearing operation on the blank in the region of the first-named sheared and pierced portions thereof, trimming said blank in the location of the sheared portions thereof while simultaneously removing a portion of scrap from points located entirely within the longitudinal edges of said blank, preforming said article to provide a flare in portions thereof while permitting movement of a portion of said article relative to said blank without affecting the position or location of the blank, and thereafter cutting said blank on a line transversely of the longitudinal edges thereof to separate said preformed article from the remainder of said blank.

2. The method of forming a plurality of metal clips of like size and formation from a single blank of metal by a substantially continuous series of die operations, which comprises the steps of preliminarily forming a portion of one of said clips extending across the entire width of said blank by shearing said blank and simultaneously forming a portion of another clip by a piercing operation, advancing said blank and performing a second shearing operation on the blank to further the completion of said second-named clip, performing a trimming operation on said blank to remove portions of the metal from points located solely within the longitudinal edges of said blank and adjacent said partially formed clips and simultaneously removing said scrap metal, subjecting one of said clips to a preforming operation to provide flared portions therein and simultaneously moving a portion of said preformed clip relative to the next adjacent clip without affecting the position or location of the metal blank, and thereafter subjecting adjacent clips to a punching operation to separate the preformed clip from said blank on a line extending transversely across the entire width of said blank and to simultaneously provide rounded edges at predetermined points on said adjacent clips.

3. The method of progressively forming metallic links for cartridge belts which comprises progressively feeding a metal strip having a predetermined width coextensive with the length of the body portion of the finished link, through a series of separate but coordinated die operations to simultaneously perform shearing, piercing, trimming and preforming operations on said strip to progressively form said links, while utilizing the entire width of said strip said performing operation causing a movement of a portion of one of the links being formed relative to the strip of which it forms a part without separating such links from the longitudinal edges of the strip or affecting the position or condition of the remainder of said strip, and thereafter transversely cutting said strip to sever each of said preformed links therefrom.

4. The method of progressively forming cartridge belt links between the longitudinal edges of a strip of metal having a predetermined width coextensive with the length of the body portion of the completed link, which comprises the steps of simultaneously shearing and piercing said strip at predetermined spaced points to remove a slug of metal from said strip in advance of said shear, again shearing the strip to interconnect the pierced portion thereof and said first sheared portion simultaneously trimming and punching the strip at the locality of the sheared portions thereof to remove portions of the metal

11

within the longitudinal edges of said strip, and thereafter moving a portion of one of said cartridge links longitudinally of the strip while simultaneously preforming said portion while remaining an integral part of said strip without effecting the movement of the remainder of the strip.

5. The method of progressively forming cartridge belt links from a strip of metal having a predetermined width coextensive with the length of the body portion of the completed link, which comprises the steps of simultaneously shearing and piercing said strip at predetermined spaced points to remove a slug of metal from said strip in advance of said shear, again shearing the strip to interconnect the pierced portion thereof and the portion of said strip at the first shear, simultaneously trimming and punching the strip at the locality of the sheared portions thereof to remove portions of the metal within the longitudinal edges of said strip, moving a portion of one of said cartridge links longitudinally of the strip while simultaneously preforming said portion while remaining an integral part of said strip

12

without effecting the movement of the remainder of the strip, and thereafter cutting said strip transversely of its edges to separate said preformed link from the strip.

6. The method of progressively forming cartridge belt links from a strip of metal having a predetermined width coextensive with the length of the body portion of the completed link, which comprises the steps of simultaneously shearing and piercing said strip at predetermined spaced points to partially form a pair of adjacent links in said strip, again shearing said strip to form additional portions of said adjacent links, removing metal from within the longitudinal edges of said strip to further the formation of the said links, preforming a portion of one of the links while simultaneously moving said portion relative to the adjacent link while both of said links remain an integral part of said strip without causing movement of the remainder of the strip, and then cutting across both longitudinal edges of said blank to separate the preformed link from said strip.

VICTOR J. DEL GIUDICE.
